P. BARKER.

DIRECT AND LATERALLY LEANING, ROCKING, FIRM STANDING, AND PIVOTAL CHAIR.
APPLICATION FILED NOV. 7, 1917.

1,301,639.

Patented Apr. 22, 1919.

UNITED STATES PATENT OFFICE.

PARRISH BARKER, OF SAN FRANCISCO, CALIFORNIA.

DIRECT AND LATERALLY LEANING, ROCKING, FIRM-STANDING, AND PIVOTAL CHAIR.

1,301,639.

Specification of Letters Patent. Patented Apr. 22, 1919.

Application filed November 7, 1917. Serial No. 201,168.

To all whom it may concern:

Be it known that I, PARRISH BARKER, a citizen of the United States, residing in the city and county of San Francisco and State 5 of California, have invented a new and useful Direct and Laterally Leaning, Rocking, Firm-Standing, and Pivotal Chair, of which the following is a specification.

An object of my invention is to provide 10 a novel rocking chair. A further object is to provide a rocking chair having functions in addition to those of rocking chairs of former construction in that the occupant may not only rock directly back and forward 15 when he chooses so to do, but he may also at will rock the chair into a sidewise leaning position, and may at will rock backward and forward in any of said positions, and may at will sit with the chair stationary in 20 either an erect or in a sidewise leaning position.

An object is to provide a rocking chair 25 which the occupant can adjust to various comfortable changes of position, erect or leaning to one side or the other in order to rest the body or in order to draw close to or move away from a reading lamp or a sewing table, without rising, and to allow the person to rock comfortably in any of the 30 various positions.

The invention is regarded as broadly 35 new, basic, and pioneer, in that it is constructed with rocker treads of different arcs, the axes of which are in angular relation 40 to each other, so that the chair may rock or stand in either an upright position or with an inclination to one or the other side at the pleasure of the occupant; and also in that it has rocker means that form a pivotal support.

The invention is regarded as broadly new, 45 basic and pioneer in that it has rocker treads constructed practically as the arcs of various cylinders, the axes of which arcs are in angular relation to each other, that is to say, 50 assuming the chair to stand normally upright, the front portions of the supporting rockers have treads formed practically as the arc of a cylinder having a horizontal axis and a predetermined radius, and the arc of said cylinder is extended rearwardly by intermediate rocker treads to support the chair in direct forward and back rocking;

the side rockers being ribs bent upward at the rear and constructed in combination 55 with the treads of intermediate rocker means that respectively conform to the arcs of two cylinders respectively which are constructed from axes that are oblique to the axis of the forward arc and to each other. 60

In practice various forms of this novel 65 rocking chair may be constructed and I shall illustrate the same in two of said forms.

The invention is capable of being carried 70 out with either one supplemental or intermediate rocker or with more than one supplemental or intermediate rocker.

An object is to provide a rocking chair 75 adapted to a variety of novel rocking and standing positions.

It is understood that the rocker treads are not exactly constructed to the arcs of cylinders and the term "practically cylindrical" is intended herein to indicate such approach to or departure from the cylindrical form as may be deemed expedient by the constructor.

It is not an object to change the form of the supporting tread of the rockers, except 80 as may be necessary to allow the chair to assume the erect and leaning positions alternately.

A further object is to enable the seated occupant to easily turn the chair around 85 pivotally without rising.

Other objects, advantages and features of 90 novelty may appear from the accompanying drawings, the subjoined detail description and the appended claims.

The accompanying drawings illustrate the invention.

Figure 1 is a typical side elevation of a 95 rocking chair embodying this invention and in erect position for rocking directly forward and back as a common rocking chair. Broken lines indicate a tilted position of said chair.

Fig. 2 is a rear elevation of a chair of 100 the quadruple rocker form in the erect position shown in solid lines in Fig. 1.

Fig. 3 is a perspective skeleton view of 105 the lower frame of the quadruple rocker chair viewed from above at the rear.

Fig. 4 is a rear sectional elevation showing 110 in solid lines the quadruple rocker chair

rocked directly back; and showing in broken lines a position of the rocker and the chair tilted to the right.

Fig. 5 is a view analogous to Fig. 3 showing the construction with a single central chair-tilting rocker.

Fig. 6 is an enlarged typical fragmental side view of the rocker of any of the foregoing views in the erect position.

10 The chair comprises a box 1 having front legs 2, 3, mounted on forward rocker portions 4, 5, and having rear legs 6, 7, mounted upon upwardly deflected rear rocker portions formed by ribs 8, 9. The rocker portions 4, 5, 8, 9 constitute side rockers. Said side rockers are connected by a brace or stretcher 10. The frame 1 has a rear cross piece 11. Intermediate rockers formed by ribs 12, 13 in the form shown in Fig. 3 are connected by suitable means as the screws or dowels 14 to the brace 10, and are connected at 15 to the rear cross piece 11 of the frame.

15 In the form shown in Fig. 5 a single intermediate rocker, 16, is shown, and this extends directly back along the midline between the side rockers.

20 By means of the side rockers and the intermediate rockers, the rocking chair is provided with various rocker treads constructed in various arcs drawn to axes that are in angular relation to each other. The front tread 17 constituted by the bottoms of the forward portions 4, 5, of the side rockers, is 25 drawn to an axis, not shown, parallel to the front cross piece 18 of the frame 1; that is to say, the transverse traces of the forward tread are horizontal when the chair is upright.

30 40 The normal bottoms 19 of the intermediate rocker means of either form of chair shown constitute a rearward continuation of the same tread, so that while the chair is in an upright position as indicated in solid lines 45 in Figs. 1, 2 and 4, the chair may be rocked backward and forward to the fullest extent the same as with an ordinary chair, the chair at its forward position being sustained by the direct tread 17 of the side rockers, 50 and in its backward position being sustained by the direct tread 19 of the intermediate rocker means shown either at 12, 13 or at 16. The side rockers, however, are provided with upwardly deflected rear sections having tread faces 20, being the bottoms of the 55 rear portions 8, 9 and adapted to form with the bottom faces 19, rear lateral treads each drawn to an axis, not shown, that is horizontal when the chair is inclined and aslant 60 as indicated by dot-and-dash lines 21 in Fig. 4 when the chair is upright. By this construction, when the chair is supported by a plane surface 22 it may be rocked directly forward and back on the combination tread 65 formed by the arc 17, and the rearward ex-

tension 19 thereof; and when the occupant so desires he may throw his weight to one or the other side of the rocking chair as he rocks back, and as the chair leaves the arc 17 of the forward tread the chair will be 70 caused to take its support from a tread formed by the side arc 20 combined with an intermediate arc 19. The chair is thus tilted sidewise in the rear rocking position indicated by the dot-and-dash lines in Fig. 4. 75

80 As a consequence of the construction hereinbefore described, the occupant of the chair is able to easily bring his body to erect position either rocking or stationary or to inclined position either to the right or left, 85 and either rocking or stationary as may be most comfortable for the time being.

85 90 The crowns a , a' of the side rocker means 8, 9 and the crowns b , b' of the supplemental or intermediate rocker means 12, 13, 95 are offset front and back, relative to each other, so as to practically form four feet intermediate the front and back of the chair when the chair is in the upright position shown in Fig. 1. The two crowns b , b' of the intermediate rocker means 12, 13, in Figs. 1 and 3 are so close to each other and to the vertical axis of the chair body, that they practically form a central pivotal support which gives the effect of one foot of a 95 tripod of which the crowns a , a' are the other two feet. This central foot practically formed by these two central rocker crowns b , b' co-acts with the widely separated side rocker crowns a , a' to give a three-footed 100 non-rocking stable or firm-standing support for the chair when upright; so that the chair in its central upright position affords comfort to a person desiring to sit steadily upright without rocking.

105 The crown b'' of the central rocker 16 shown in Fig. 5 affords a like support when desired. This non-rocking or firm-standing character is changed by tilting the chair back or forward; and when the chair is 110 tilted back the intermediate rocker means 12, 13 will act as is the case with common rockers for rocking directly back and forward; and, since the tread of the intermediate rocker means widens rearwardly in 115 the form shown at 12, 13 in Figs. 1 and 3, the farther back the rocking chair of that form is rocked, the more positive is the support of its active rocker means or tread against any lateral tilting or leaning. 120

125 The lateral tilting or leaning of the chair is easily effected by the occupant by simply first bringing the chair to the upright position, and there simultaneously leaning to one side and tilting back. The chair is thus made to lean and may be rocked to and fro at will; or may be brought to rest in the leaning and tilting position.

130 By returning to the stable position and then rocking back somewhat so that the

chair is supported by only the central pivotal foot formed by the two intermediate rocker crowns b , b' in Figs. 1 and 3, the chair may be rotated as on a pivot.

5. A like position with the form shown in Fig. 5 allows the chair to pivot on crown b'' .

I claim:—

1. A rocking chair having its rocker tread constructed of ribs in various arcs drawn to 10 axes that are in angular relation to each other at front and back of the tread.

2. A rocking chair having its rocker tread formed of ribs and having a forward portion of its rocker tread constructed to an 15 arc drawn to an axis that is horizontal when the chair is erect, and having at the rear of such arc, a rocker tread constructed to an arc drawn to an axis that is inclined to said horizontal axis so that the chair leans to one 20 side when the chair rests on such rear rocker tread.

3. A rocking chair having side rockers constructed to form a forward tread and a rearward tread, the rear tread being within 25 the produced periphery of the forward tread, and one or more intermediate rockers co-operating with the side rockers to constitute two rocker treads constructed to arcs, the axes of which are oblique to the axis of the 30 forward tread.

4. A rocking chair provided with two side rockers and two intermediate rear rockers, the treads of the intermediate rear rockers forming practical rearward extensions of 35 the forward tread of the side rockers; the portions of the side rockers rearward of the front treads of said side rockers being bent upward inside of the produced arc of the forward treads of said side rockers.

40. 5. A rocking chair having a forward tread formed of ribs the transverse traces of said tread being horizontal when the chair is erect, and a rearward tread formed by other ribs, the transverse traces of said rearward tread being aslant when the chair is erect.

6. A rocking chair having a forward tread and a rearward tread the transverse traces of which are horizontal when the 50 chair is erect, and two lateral treads rearwardly of the forward tread; the transverse traces of said lateral treads being in angular relation to each other and aslant when the chair is erect.

55. 7. A rocking chair having rocker means provided with treads, the transverse faces of which are level when the chair is in one position and having other rocker means, the transverse traces of which are aslant when

60 the chair is in said position, there being intermediate rocker means for supporting the chair as it shifts from the support by one of said rocker treads to the support formed by the other of said rocker treads.

65. 8. A rocking chair having rocker means

for supporting the chair at one angle at one position and having rocker means for supporting the chair laterally inclined to such angle in another position.

9. A rocking chair having a pair of side 70 rockers formed with a tread, one section of which practically conforms to the periphery of a cylinder the axes of which are normal to the transverse traces of the chair, and having rocker sections composed of ribs 75 conforming to a segment of a cylinder, the axis of which is oblique to said traces.

10. A tilting rocking chair having rocker sections at the front with treads conforming to a segment of a cylinder having an 80 axis in parallelism with transverse traces of the seat of the chair, said chair also having two sets of rocker sections, the rocker sections of each set conforming practically to segments of cylinders having axes oblique 85 to each other and oblique to the transverse traces of the chair seat.

11. A rocking chair having side rocker means for supporting the chair in one position and intermediate rocker means between the side ribs for supporting the chair in another position; the crown of the side rocker ribs being forward relative to the crown of the intermediate rocker ribs, so as to form a stable support for the chair 95 in one position.

12. A rocking chair having side rocker means for supporting the chair in one position and intermediate rocker means between the side ribs for supporting the 100 chair in another position; the crown of the side rocker ribs being forward relative to the crown of the intermediate rocker ribs so as to form a stable support for the chair in one position; and the crown of the intermediate 105 rocker means forming a pivotal support when the chair is rocked back somewhat.

13. A rocking chair having side rocker means for supporting the chair in one position and intermediate rocker means for supporting the chair in another position; the crown of the side rocker means being forward relative to the crown of the intermediate rocker means so as to form a stable 115 support for the chair in one position; and the crown of the intermediate rocker means forming a pivotal support when the chair is rocked back somewhat; the intermediate rocker means comprising two rockers diverging from each other rearwardly to contact respectively with the side rocker means to support the chair and allow it to rock in a laterally leaning position.

14. A rocking chair having rocker means 125 provided with crowns that are offset relative to each other to form a stable support for the chair at one position; said rocker means being provided with various treads drawn to different axes which are oblique 130

to each other so that in one position the
chair may be rocked directly forward and
back, and in another position it is supported
in a laterally leaning position and may be
5 rocked while thus supported leaning to one
side.

In testimony whereof, I have hereunto set
my hand at San Francisco, California, this
31st day of October, 1917.

PARRISH BARKER.
